UNITED STATES PATENT OFFICE.

LUCIUS HENRY WHITTREDGE, OF LYNN, MASSACHUSETTS.

PORTABLE BUILDING.

Application filed October 5, 1925. Serial No. 60,431.

My invention relates to buildings, and particularly to the so-called portable type. It has for its objects, to provide improved means adaptable to support an inner lining for a building, both sides and roof, or for partitions therein; to provide a standard construction adaptable for use with or without a lining or inner wall, and to which an inner lining of sides or roof can be added later, if first constructed single; to provide an improved construction forming an air space of any desired thickness between the inner and outer walls and the roof and inner lining of the roof; to provide novel means adaptable to support the roof or outer wall of a building independent of the inner wall, without contact with the inner wall, and without depending on said inner wall; to provide an improved building support designed to pass through and hold the inner wall or roof lining, and functioning also as a support for the outer wall or roof; to provide an efficient means for holding the lining of the roof, or inner wall in position, without decreasing the weight carrying capacity of the walls and roof; to eliminate weight on the inner walls and roof lining; and to provide various other advantages and results made apparent from the following specification.

I accomplish the objects of my invention as disclosed in the accompanying drawings, which form a part of this specification and in which Figure 1 shows the detail of the locking unit adaptable to hold the inner wall in position, along side the outer wall. Figure 2 shows the detail of the inner wall supporting member or upright. Figure 3 shows the function of the locking unit at the base of the inner wall supporting member, at its base, intermediate its base and top, and at its top. Figure 4 shows a section of the inner wall in finished form.

Referring again to Figure 1, F shows the outer wall, G shows the inner wall, H shows the inner wall supporting member, I shows the locking unit which holds the inner wall in position along side the outer wall.

Referring again to Figure 1, J shows that portion of the locking unit I which when the unit is inverted for use at the top of the inner wall supporting member (as shown in Figure 3) is bent down over the top of the supporting H so as to hold it in fixed position while its opposite end K locks up under the top plate. Referring again to Figure 3,

L shows the top plate. M shows the cross beam over which the locking unit I fits at its portion K. N shows the sill of the building over which the portion K of the locking unit I also fits.

The locking unit I is shaped at one end to engage and hold within the inner wall supporting member and is optionally in fixed position or slidable to any point where it can readily engage, at its opposite end K, the cross beams, seams, or sill of the building in which it is used. In its inverted position it also readily engages the top plate, thus affording adequate and substantial means for holding the inner wall firmly in position. No locking unit is required in my improved double roof construction, the weight of the lining being sufficient to hold same in place. The wall construction described can as well be applied for partitions within a building.

Similar characters of reference refer to similar parts throughout the various views.

It is readily seen that the construction disclosed renders the assembling of so-called portable buildings, lined or to be lined, a simple matter, and that the structure is substantial and well adapted to withstand more than ordinary requirements.

Having thus described my invention I claim as new and desire to secure by Letters Patent of the United States of America:

1. In a double wall building construction, upright framing members having relatively spaced apart web portions, said framing members supporting an inner wall of the building, horizontal stringers spacing an outer wall from the inner wall, and a locking member for attaching the outer wall to the inner wall, said locking member being formed with a body portion one end of which is receivable between the spaced webs of the upright framing members, and means on the locking member for engaging the horizontal stringers and the upright framing members for the purpose defined.

2. In a double wall building construction, upright framing members having relatively spaced apart web portions, said framing members supporting an inner wall of the building, horizontal stringers spacing an outer wall from the inner wall, and a locking member for attaching the outer wall to the inner wall, said locking member being formed with a body portion and flanges at its ends, one end of the body portion being receivable between the spaced webs of the

upright framing member, and the flange at the said end of the body portion being bent to lock the same therein, and the flange at the other end of the body portion engaging about the horizontal stringers.

3. In a double wall building construction, framing members formed with a pair of doubly flanged elements having webs which are relatively spaced from each other, the flanges of the elements extending in opposite directions, said framing members supporting an inner wall of the building, horizontal irons spacing an outer wall from the inner wall, and means engaging said framing members and said horizontal irons for locking the same together in the assembly of the wall.

4. In a double wall building construction, framing members formed with a pair of doubly flanged elements having webs which are relatively spaced from each other, the flanges of the elements extending in opposite directions, said framing members supporting an inner wall of the building, horizontal angle irons spacing an outer wall from the inner wall, and a locking member for attaching the outer wall to the inner wall, said locking member being formed with a body portion and flanges at its ends

extending at right angles to the body in the same direction, one end of said body portion being receivable between the spaced webs of the framing member, and the flange at the said end of the body portion being bent to lock the same therein, the flange at the other end of the body portion engaging about the angle iron.

5. In a double wall building construction, framing members formed with a pair of doubly flanged elements having webs which are relatively spaced from each other, the flanges of the elements extending in opposite directions, said framing members supporting an inner wall of the building, horizontal angle irons spacing an outer wall from the inner wall, and a locking member for attaching the outer wall to the inner wall, said locking member being slidable with respect to said framing member and horizontal angle iron to its proper position, and having a body portion one end of which is receivable in the space between the webs of the framing member, the ends of said locking member being formed with bent portions engaging about said framing member and angle irons to hold the same together.

In testimony whereof I affix my signature.

L. HENRY WHITTREDGE.
